UNITED STATES PATENT OFFICE.

HENRY BENJAMIN GORMAN, OF CAMBRIDGE, MASSACHUSETTS, ASSIGNOR TO UNITED SHOE MACHINERY CORPORATION, OF PATERSON, NEW JERSEY, A CORPORATION OF NEW JERSEY.

SHOE.

Application filed August 15, 1919. Serial No. 317,706.

To all whom it may concern:

Be it known that I, HENRY BENJAMIN GORMAN, a citizen of the United States, residing at Cambridge, in the county of Middlesex and State of Massachusetts, have invented certain Improvements in Shoes, of which the following description, in connection with the accompanying drawings, is a specification, like reference characters on the drawings indicating like parts in the several figures.

This invention relates to improvements in the manufacture of soles for boots and shoes and more especially to improvements in soles of the type having a marginal rib or shoulder to receive the stitches for attaching a shoe upper to the sole.

The invention is herein shown and described for convenience in illustration, but not at all by way of limitation, as embodied in soles for use in the manufacture of turn shoes and particularly turn soles of the type disclosed in United States Patent No. 1,286,176, granted on an application of

George Ferguson.

One of the requisites of good shoemaking is to produce a proper fitting and strong connection of the constituent parts of the shoe at or near the heel breast line. This is very difficult to secure with soles having sewing ribs such as heretofore used because the sewing rib terminates abruptly at substantially the heel breast line of the sole and therefore does not offer the same resistance to the outwardly directed strain of the shoe upper that it does throughout other portions of the rib. This difficulty is further increased because of the additional thickness of the counter material at the heel breast line which makes it necessary to use a much stronger seam in order to bring the counter and upper materials into proper relation to the sewing rib.

Moreover, in the manufacture of turn shoes in which the sole is provided with a sewing rib which terminates abruptly at or near the heel breast line of the shoe, further difficulties are experienced in incorporating a molded counter in a shoe for the reason that the forward portion of the molded counter is necessarily seated upon the ends of the sewing ribs on either side of the sole which raises the end of the counter off the

sole and tips it backwardly on the sole with the result that the upper is distorted and loose particularly adjacent to the lower edge of the counter.

The present invention has for an object to produce an improved sole so constructed and arranged with respect to the sewing rib that a more accurate and better fitting and stronger anchorage of the constituent parts of the shoe at or near the heel breast line may be obtained.

With this object in view the invention contemplates an improved sole of the type having a marginally extending sewing rib to receive the stitches for the attachment of a shoe upper, which sole has the base of the sewing rib along its inner side in the region of the heel breast line in a lower portion than at other portions of the sole. As herein illustrated, this is accomplished by providing local depressions in the upper surface of the sole adjacent to the inner wall of the sewing rib. By reason of these depressions in the sole it is possible to present the shoe to the sewing instrumentalities at such an angle that the stitches are formed in a plane extending downwardly as distinguished from the substantially horizontal plane of the stitches through the fore-part of the shoe so that the stitches are caused to draw the upper materials further inwardly over the shoe bottom and snugly against the sewing rib. Of course the presentation of the shoe to the sewing instrumentalities controls the plane in which the stitch is to be formed but even though the shoe is presented to the machine in substantially the same plane throughout, the depressions allow the shoe to be raised when sewing through the shank so that the needle is forced deeper into the sewing rib which causes the stitches to draw the upper materials, including the counter portion for example, into the angle formed by the feather and the sewing rib of the sole to better advantage.

In accordance with a further feature of the invention the sewing rib on the sole is progressively decreased in height rearwardly from points approximately midway of the shank portion of the sole and preferably, also, the depressions in the sole are progressively increased in depth rear-

wardly. As illustrated, the decrease in height of the sewing rib corresponds to the increase in depth of the depressions. In this way the shoulder produced by an abrupt termination of the sewing rib as heretofore constructed is eliminated, so that in practice the sole and forward portion of the heel for the shoe may be seated solidly upon the sole proper. A sole having a sewing rib constructed as described is particularly applicable to the manufacture of turn shoes of the type in which a previously molded counter is incorporated in the shoe, which method of making turn shoes is now being extensively practised. In the molded counter method of making turn shoes the molded counter is seated upon the upper side of the sole after the upper has been sewed to the sole, and inasmuch as the counter usually extends a distance beyond the heel breast line of the shoe, the forward portion of the counter has to be seated upon the sewing rib. Where the sewing rib terminates abruptly and forms a shoulder, as with prior constructions, it is obvious that the forward end of the counter is raised from the surface of the sole by the sewing rib which prevents a satisfactory attachment of the counter in position on the sole. However, by reason of the beveled terminals of the sewing rib construction provided by this invention this disadvantage is eliminated.

Other objects and features of the present invention will appear from the following description when considered in connection with the accompanying drawing which illustrates a preferred embodiment of the invention and the novel features of the invention will then be pointed out in the appended claims.

Fig. 1 is a perspective view of a sole made in accordance with the present invention;

Fig. 2 is a sectional view on the line 2—2 of Fig. 1 and illustrating the use of the sole in the manufacture of a turn shoe having a molded counter;

Fig. 3 is a cross-section illustrating the attachment of the shoe upper to the sole on the line 3—3 of Fig. 1;

Fig. 4 is a cross section illustrating the attachment of the shoe upper to the sole on the line 4—4 of Fig. 1, and

Fig. 5 is a sectional detail showing the arrangement of the constituent shoe parts in the region of the heel breast line after the shoe is turned.

The illustrated sole which is of the type disclosed in the above-mentioned application comprises a body portion 2 of rubber or like material and a sewing rib 4 molded along the upper marginal surface of the sole, the sewing rib terminating at substantially the heel breast line of the sole on either side. Soles of this general character either for welt or turn work and made of leather or composition as heretofore constructed provide a sew-

ing rib structure in which the base or root of the rib along its inner side occupies substantially the same plane throughout and which terminates abruptly at substantially the heel breast line of the sole. In accordance with the present invention the upper surface of the sole 2 adjacent to the inner walls 5 of the sewing rib 4 is provided with depressions 6 extending from a point forwardly of the heel breast line and about midway of the shank portion to the termination of the sewing rib at the heel seat portion of the sole. These depressions 6 preferably increase in depth rearwardly and are of sufficient width to give clearance to the sewing needle of a sewing machine as it emerges from the inner wall of the rib during the sewing operation. By reason of these depressions it will be seen that the base or root 8 of the rib 4 adjacent to the depressions is located in a lower plane than is the base of the rib throughout other portions of the sole. Consequently when a shoe upper is being attached to the sole the sewing machine operator, when sewing in the region of the heel breast line, is enabled to manipulate or tip the shoe as illustrated in Fig. 3 so that the sewing instrumentalities can form the stitch in a lower plane along the inside rib than through the forepart of the sole.

The line a—a (Fig. 4) indicates the path of the sewing machine needle relatively to the sole when sewing through the forepart of the shoe. It will be noted that the stitch 9 lies in a plane substantially parallel to the tread plane of the sole and the tension of the stitch 9 is in a direction nearly at a right angle to the perpendicular walls of the sewing rib 4. The line b—b (Fig. 3) indicates the path of the needle when advantage is taken of the depressions 6 and the shoe tipped so that the stitch 9 is formed along the base of the inner wall 8 of the rib. The stitch 9 at this point lies in a plane which is inclined inwardly and downwardly relatively to the tread plane of the sole instead of substantially parallel to the tread plane as in the forepart. Also, the strain of the stitch on the upper materials is at a more acute angle to the perpendicular walls of the rib 4 than through the forepart as shown in Fig. 3. In fact, the path of the needle when sewing in the region of the breast line substantially bisects the angle formed by the feather 12 of the sole and the outer wall of the rib 4 which insures the upper materials being drawn by the stitches into the vortex of this angle. The result of this is to cause the stitches 9 locally of the heel breast line to draw the upper materials farther inwardly over the feather and tightly against the rib, thus taking up any excess fullness of upper materials about the last. It will be appreciated that in instances where the heavy counter terminals

of a shoe are included with the upper materials at the breast line, the above described construction and arrangement of the stitches is particularly advantageous. Moreover, by laying the inner termination of the stitches deeper into the body of the sole (Fig. 3) not only is the holding power of the stitch increased but there is little, if any, opportunity for the tensioned upper to pull the ends of the sewing rib outwardly and thus allow the upper to slacken and present a loose and bulged appearance at the heel breast line of the shoe. This latter advantage is of considerable practical importance, particularly with the manufactured type of insoles for welt shoes inasmuch as the heavy counter material, in addition to the upper stock, places the terminals of the sewing rib under a continuous outward strain which, unless counteracted, as by the attachment of the heel to the shoe, results in a bulky and undesirable appearance of the shoe upper along the shank.

As herein shown the sewing rib 4 is also decreased in height rearwardly from a point on either side of the sole about midway of the shank portion to the heel seat portion, this decrease preferably corresponding to the increased depth of the depressions 6. These sloped terminal portions 10 of the sewing rib, during the sewing operation, co-operate with the depressions 6 to enable the upper materials to be drawn farther inwardly on to the insole by the inseam stitches. Further, the edges of the upper materials and also the counter, if included in the inseam, being drawn inwardly and downwardly, are caused to lie more flatly on the surface of the sole, thus reducing the shoulder heretofore produced by the abrupt termination of the ribs.

By forming depressions 6 in the surface of the sole adjacent to the sloped terminal portions 10 of the rib in the manner above described, the normal height of the inner walls 5 of the rib is retained so that the strength of the between-substance of the sole is not impaired while the outer wall of the rib provides an adequate striking shoulder for the sewing needle because of the angular presentation of the shoe to the sewing needle.

In the use of this sole for the manufacture of turn shoes, and especially turn shoes with molded counters, the described structure of the sewing rib will be found particularly advantageous. With the method of manufacturing turn shoes illustrated in Fig. 2 of the drawing and known as the "Thissell" method, a molded counter 14 is attached in upright position on the heel end 15 of the sole after the upper 16 has been secured to the sole and before turning the shoe right side out. The counters invariably extend a considerable distance forwardly of

the heel breast line of the shoe and into the shank. When such a counter is applied to a turn sole in which the sewing rib 4 terminates abruptly at the heel breast line, its end portion is necessarily seated on the shoulder which inclines the counter and throws it out of its correct relative position in the shoe with a resulting distortion of the shoe upper. Moreover, this inclined position of the counter on the sole produces an excess fullness of upper material adjacent to the feather of the sole. It will be noted that in the use of a sole in which the sewing rib is sloped rearwardly from the ends of the counter, the counter may be solidly and evenly seated on the sole and the shoe upper attached to the sole so that it will accurately conform to the molded lines of the counter.

Although the invention has been illustrated and described as embodied in an outsole of the type used in the manufacture of turn shoes, it should be understood that the invention is not limited in the scope of its application to this particular article and that the word sole as used in the claims is entitled, when not otherwise limited, to cover insoles as well as outsoles.

Having thus described my invention, what I claim as new and desire to secure by Letters Patent of the United States is:

1. As an article of manufacture, a sole for shoes provided with a marginally extending rib to receive stitches for the attachment of a shoe upper, and a depression adjacent to the inner wall of said rib, those portions of the depression adjacent to the inner wall of said rib at or near the heel breast line of the sole being deeper than the remaining portions.

2. As an article of manufacture, a sole for shoes provided with a marginally extending rib to receive stitches for the attachment of a shoe upper and having the base of the said rib at its inner side in the region of the heel breast line in a lower plane than at other portions of the sole.

3. As an article of manufacture, a sole for shoes provided with a marginally extending sewing rib to receive stitches for the attachment of a shoe upper, said sewing rib decreasing in height rearwardly at or near the heel breast line of the sole and having depressions adjacent to the inner wall of the sewing rib to maintain a uniform height for the inner wall of the said rib.

4. As an article of manufacture, a sole for shoes provided with a marginally extending rib to receive stitches for the attachment of a shoe upper and having depressions increasing in depth rearwardly along the inner wall of the sewing rib at or near the heel breast line, said sewing rib decreasing in height corresponding to the increasing depth of the said depressions.

5. As an article of manufacture, a sole for

shoes provided with a marginally extending rib to receive stitches for the attachment of a shoe upper and having the inner wall of the said rib locally of the heel breast line uniformly increased in depth rearwardly.

6. As an article of manufacture, a sole for shoes provided with a marginally extending rib to receive stitches for the attachment of a shoe upper and having the inner wall of the said rib locally of the heel breast line uniformly increased in depth rearwardly therefrom and the height of said rib above the upper surface of the sole decreased cor-

responding to the increased depth of the inner wall.

7. As an article of manufacture, a molded and vulcanized sole provided with a marginally extending rib to receive stitches for the attachment of a shoe upper, the inner wall of the rib in the region of the heel breast line extending to a lower level than does the inner wall of the rib throughout the remainder of its extent.

In testimony whereof I have signed my name to this specification.

HENRY BENJAMIN GORMAN.
